UNITED STATES PATENT OFFICE.

MADELINE M. HERSHEY, OF LOS ANGELES, CALIFORNIA.

GARMENT.

1,398,720.

Specification of Letters Patent.

Patented Nov. 29, 1921.

Application filed August 19, 1920. Serial No. 404,569.

To all whom it may concern:

Be it known that I, MADELINE M. HERSHEY, a citizen of the United States, residing at Los Angeles, in the county of Los Angeles and State of California, have invented a new and useful Garment, of which the following is a specification.

This invention relates to a garment and is more particularly directed to a combination 10 skirt and trousers.

The object of the invention is to provide a combination dress skirt and riding trousers or breeches, adapted to be worn as a dress skirt with the trouser sections positioned between the skirt and the wearer, or to have its various sections joined together and applied to the wearer with the front portions of the skirt coöperating with the trouser sections to form a complete pair of trousers, 20 and the back skirt section maintaining its skirt form.

A further object is to provide a garment having the above characteristics, with attaching and joining means by which the garment may conveniently and rapidly be converted from one form to the other.

Various other objects and advantages will be more fully apparent from the following description of the accompanying drawings 30 which form a part of the disclosure, and which illustrate a preferred form of embodiment of the invention.

Of the drawings,

Figure 1 is a front elevation of the garment in skirt form.

Fig. 2 is a rear elevation thereof.

Fig. 3 is a view showing the skirt sections opened to disclose the trouser sections.

Fig. 4 is a vertical section on line X⁴—X⁴ 40 of Fig. 3.

Fig. 5 is a plan section on line X⁵—X⁵ of Fig. 3.

Fig. 6 is a view similar to Fig. 3 showing the trouser sections joined at the crotch.

Fig. 7 is a front elevation showing the garment applied in trouser form.

The garment has the belt 2 to which the various sections are secured, preferably by being gathered at the waist line and stitched thereto. The skirt of the garment comprises two opposed back and side sections 3—3 joined together at the rear of the garment to a point 4. The front vertical edges of the sections 3 are folded inwardly in plait formation (see Fig. 5) and are joined at 55 5—5 to front panel sections 6—6. These

panels have at their lower portions, two buttons 7 and companion button holes 8, the purposes of which will hereinafter be pointed out. When worn in skirt form the vertical 60 edge of the right hand panel section 6 overlaps the left hand panel section, the abutting surfaces of the panels having coöperating snap members 9 secured thereto.

The trouser portion of the garment comprises two breech and leg sections 10—10 secured to the belt beneath the skirt sections 3—3 the inner edges of the sections 10—10 being joined part way of their length downwardly from the belt to a point 11 (see Fig. 70 3) and from the point 11 downwardly, the inner edges of the sections 10—10 turn outwardly and join the vertical edges of the front panel sections 6—6 forming trouser legs open toward the inner surface of the 75 skirt and having free inner edges 12—12. The sections 10—10 are therefore joined to the skirt only at the belt and at the vertical edges of the panels 6—6. The lower ends of the trouser sections 10—10 are gathered as at 80 13—13 and attached at 14 to the edge 12 and at 15 to the outer fold of the leg section 10 there is an elastic tape 17 connecting the under and the upper plies of each trouser leg and serving to cause the lower end thereof to 85 closely fit the limb of the wearer immediately above the knee.

Attached to the outer surface of the right leg section near the upper crotch edge thereof is attached two snap sections 18—18 90 and attached to the inner surface of the left leg section in coincident relative locations are two companion snap sections 19—19 adapted for engagement with the snap sections 18—18 when the garment is applied 95 in trouser form as will later be explained. Near the gathered edge of each leg section is a snap section 20 which coöperates with a companion snap section 21 attached to the inner surface of the garment near the marginal edge of the adjacent panel section 6 when the garment is worn in trouser form.

In use as a dress skirt the garment is drawn around the body and the coöperating snap sections 9 are engaged to close the front of the skirt, the trouser leg sections being permitted to hang free between the skirt and the body.

In use in trouser form the limbs are inserted into the trouser legs, the lower gathered ends thereof being positioned immediately above the knees, and the snap sections

- 20 engaged with the snap section 21 so that the inner edges of the panel sections 6—6 thus become secured to the bottoms of the trouser legs (see Figs. 6 and 7).
- 5 The snap sections 18 are engaged with the snap section 19 to join the crotch edges of the trouser leg sections 10—10, as shown in Fig. 6, and the two top snap members 9 are joined to connect the upper portions of the 10 panel sections 6—6 (see Fig. 7). With the garment thus applied, as shown in the right half of Fig. 7, the lower portions of the panel sections 6—6 are wrapped around the limbs below the knees and the buttons 7 inserted into the companion button holes 8, the lower ends of said panels thus coöperating with the trouser leg sections to form complete trouser legs, as shown in the left half of Fig. 7.
- 15 20 Of course it will be understood that the use of the snaps shown, is optional as other fastening means such as hooks and eyes or buttons and button holes, may be utilized if desired.
- 25 30 The above described garment provides a skirt comprising back and side sections and front panel sections, and inner trouser sections adapted to be joined to form trouser legs sections, which coöperate with the panels to form a complete pair of trousers, with the back and side skirt sections maintaining their original skirt form.
- I claim—
1. A garment combining a skirt having opposed front panels and a back section attached to a belt, a trouser portion suspended from the belt beneath the skirt, means connecting the free edges of the panels to form a dress skirt in one instance, and means attaching the lower portions of the front panels around the limbs of the wearer in a second instance, the panels forming fronts of the trouser legs and trouser cuffs below the knees and the back section maintaining its normal skirt formation.
2. A garment combining a skirt having opposed front panels and a belt, means connecting the panels, a trouser portion suspended from the belt beneath the skirt and attached to the vertical free edges of the skirt panels, the trouser sections providing trouser legs of knee length and each skirt panel adapted to form the front of each trouser leg with the lower portion thereof forming a trouser cuff encircling the limb of 55 the wearer below the knee.
3. A garment combining a skirt having opposed front panels and side and back sections attached to a belt, a trouser portion suspended from the belt beneath the skirt and attached to the vertical free edges of the skirt panels, means connecting the free edges of the skirt panels to form a dress skirt in one instance, and means attaching the lower portions of the front panels around the limbs of the wearer in a second instance, the panels forming the fronts of the trouser legs and trouser cuffs below the knees.
4. A garment comprising a convertible dress skirt and trousers, and combining an outer skirt portion having opposed front panels and a belt, and an inner trouser portion suspended from the belt and attached to the vertical free edges of the skirt panels, the trouser portion forming trouser legs of 75 knee length and having free breech edges, coöperating fastening means on the free edges of the skirt panels, coöperating fastening means on the breech edges, and coöperating fastening means at the lower portion of 80 each skirt panel, whereby the free edges of the panels may be attached to form a dress skirt, or, the free breech edges may be attached to close the breech of the trouser portion and the lower portions of the panels 85 may be secured around the limbs of the wearer below the knee, with the panels forming the fronts of the trouser legs.
5. A garment combining a skirt portion having opposed front panels, and a belt, a 90 trouser section suspended from the belt beneath the skirt portion and attached to the free vertical edges of the panels, and attaching means whereby the edges of the panels may be joined to form a dress skirt in one instance, and other attaching means securing the lower portions of the panels around the limbs of the wearer below the knees with the panels coöperating, in a second instance, to form a pair of trousers, the side and back 95 sections of the skirt portion retaining their skirt form.
- Signed at Los Angeles, California this 12th day of August, 1920.
- MADELINE M. HERSHÉY.
